UNITED STATES PATENT OFFICE.

ANDREW C. HALTERMAN, OF BUCKHANNON, WEST VIRGINIA.

HOSPITAL-BED SHEET.

No. 892,047.

Specification of Letters Patent.

Patented June 30, 1908.

Application filed March 2, 1908. Serial No. 418,776.

To all whom it may concern:

Be it known that I, ANDREW C. HALTERMAN, a citizen of the United States, residing at Buckhannon, in the county of Upshur and State of West Virginia, have invented certain new and useful Improvements in Hospital-Bed Sheets, of which the following is a specification.

My invention relates to a hospital bed sheet and consists in the construction and arrangement of parts which will be herein-after fully described, illustrated in the drawings and particularly pointed out in the claims.

One object of my invention is to provide a cheap and convenient method of restraining within comfortable limits sick persons who may be delirious, and insane persons whom it may be necessary to restrain from violent movements, and to prevent them from throwing off the bed covers; also children who are in the habit of kicking off the covers while in bed.

A further object, therefore, of my invention is to provide a strong and durable receptacle which is easily managed and readily arranged for such persons as I have mentioned above.

I am aware that what are termed "strait jackets" have been provided for the purpose of confining insane patients in one position. My invention is not designed to take the place of strait jackets, but, on the contrary, to give the patient comparative freedom of movement within the receptacle for the body.

These objects I accomplish by the structures represented in the drawings forming a part of this application, in which like numerals represent similar parts and in which:

Figure 1 is a perspective view of my improved hospital bed sheet, as applied to a body for the purpose above stated. Fig. 2 is a top plan view of my sheet which may be applied to any suitable bed. Fig. 3 is a longitudinal sectional view cut through line 3—3 of Fig. 2. Fig. 4 is a transverse section cut through line 4—4 of Fig. 2. Fig. 5 is an enlarged section of a detail modification of my invention. Fig. 6 is also an enlarged section of a modified form of eyelet as applied to my invention.

In the drawings, 1 indicates the bedstead or the couch on which the patient or person lies: 2 is the hospital sheet spread over the patient or person in the bed and secured to

the bedstead by cords 2'. The sheet 2 has a tuck 3 across the upper end. This tuck serves as a fastening device for the upper end of the leaves 4 by means of lacings 3' in eyelets 3". The lower ends of the leaves 4 are also secured in place by like lacings 3' and eyelets 3".

Extending lengthwise of the sheet is an opening 5, provided on either side with leaves 4, presumably equal to one-half of the width of the sheet. These leaves have eyelets on either side of the opening 5 and are laced together by cords or lacings 3'. Said leaves to extend from about one and one-half feet from the top of the sheet 2 to the bottom.

It will thus be seen that this improved hospital sheet may be safely and securely placed over a patient or person, and the person, if need be, secured to the bed by laying the person on the bed and placing my sheet over him and then securing the ends and sides as above described. The person is thereby well and comfortably secured on the bed or couch without harsh or unpleasant means. This is the great object of my invention, and one for which there has been a long felt want.

It is found necessary, in the construction and arrangement of my hospital bed sheet, to find plenty of room for the patient and thus it is found necessary to provide not only a good sized bed or couch but also to construct the sheet so that it can be easily and readily secured to the bed or couch, and also to employ means for covering and securing the patient or person on the bed and in the sheet.

Attention must also be given to the different sizes of persons who may be placed upon the bed and covered by my sheet. For the purpose of accommodating these persons under unusual conditions, I provide the structures shown in Figs. 5 and 6. This provision for enlargement of parts will permit of arranging the sheet and its holder to suit the conditions of any person, large or small, and thus provide for the long felt want.

In operation, the sheet having been placed upon the bed or couch, will be opened on the line 5, and the person to be operated upon placed on top of the bed or couch. This done, the leaves 4 of the sheet placed over the person, loosely or tightly as circumstances may require, will be fastened by means of the cords, as hereinbefore described.

The object of this invention is to provide a comfortable bed with a securing cover, so

that persons needing specific treatment may be gently cared for.

Having thus described my invention, what I claim and desire to secure by Letters 5 Patent, is:—

As an article of manufacture, a hospital bed sheet comprising a main rectangular sheet provided with means to secure the same to the bed or couch, a supplemental re- 10 ceptacle formed of longitudinal and laterally

closing leaves, means for securing said leaves together, a tuck and means for securing the bottom of the leaves in place, substantially as described.

In testimony whereof I affix my signature, 15 in presence of two witnesses.

ANDREW C. HALTERMAN.
